UNITED STATES PATENT OFFICE.

CHARLES H. FRASARD, OF DETROIT, MICHIGAN.

DESIGN FOR A WATCH-HOLDER.

44,094.

Specification for Design.

Patented May 27, 1913.

Application filed March 31, 1913. Serial No. 758,039. Term of patent 14 years.

To all whom it may concern:

Be it known that I, CHARLES H. FRASARD, a citizen of the United States, residing at Detroit, in the county of Wayne and State of Michigan, have invented a new, original, and ornamental Design for Watch-Holders, of which the following is a specification, reference being had to the accompanying drawing, forming part thereof.

The figure is a perspective view of a watch holder, showing my new design.

I claim:

The ornamental design for a watch holder, as shown.

CHARLES H. FRASARD.

Witnesses:

ADA W. DAVIS,
LEWIS A. STONEMAN.
